Primary Examiner — Kendra Leslie Hamilton(74) *Attorney, Agent, or Firm* — BEKIARES ELIEZER LLP(57) **CLAIM**

The ornamental design for an insect veil for horse as shown and described.

DESCRIPTION

FIG. 1 is a perspective view of an insect veil for horse, shown in condition of use for clarity of disclosure;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom thereof.

In the drawings, the broken line showing of a horse depicts environmental subject matter and forms no part of the claimed design.

The drawings are shaded to indicate contrasting surfaces.
